FEED-WATER HEATER

Arthur Scrivenor, Richmond, Va.

Application March 30, 1933, Serial No. 663,455

11 Claims. (Cl. 122—425)

My invention relates to feed-water heaters for locomotives, and particularly to those heaters which utilize heat of the exhaust steam, and heat from the hot gases on their way from the fire-box 5 to the stack.

It has for its object the providing of a heater which shall be built at a reasonable cost, which shall be easily installed in the front end of a locomotive, which shall be adapted for installation in 10 front ends of different diameters, which shall form a path for the feed-water in the flow of hot gases and of exhaust steam, and which shall absorb waste heat in such amount as will greatly lower the cost of fuel per ton-mile.

15 My invention is an improvement on the feed-water heater for locomotives designed by J. H. Kidwell, and patented by him under Number 1,567,514; December 29th, 1925. In the Kidwell heater, and in my heater, concentric bent tubes 20 are placed in the path of the hot gases. The feed-water passes between the inner tube and the outer tube. Exhaust steam from the cylinders passes through the inner tube on its way to the stack.

A great desideratum of any feed-water heater 25 utilizing the heat from exhaust steam is that it shall not obstruct the flow of the steam so as to cause appreciable back pressure on the piston of the engine from which the steam is taken. My heater provides ample passage for the flow of the 30 steam without causing appreciable back pressure. This fact has been proved by very carefully made tests.

In the drawings which accompany this specification, Figure I is a vertical section on the axis 35 of the locomotive smoke-box or front end, showing my heater in place, and also in vertical section. Figure II is a vertical section of my heater in an erect position, and it also shows a part of the front end of the locomotive to indicate the relative position of the heater therein.

40 In Figure I the numeral 1 indicates the shell of the locomotive smoke-box; 2 the smoke-box door-ring; 3 the opening to the stack, (the stack itself is not shown); and 4 the saddle of the cylinder 45 block. In Figure II also the saddle is shown at 4.

On the exhaust steam outlet 5 in the cylinder block there is usually mounted an exhaust nozzle, the opening in the end of which regulates the intensity of the steam blast under the stack. I remove the old exhaust nozzle, and in its place 50 mount my exhaust nozzle 6.

55 My nozzle is the same as the standard nozzles in use, but it has in addition flanged openings 7 and 8 on either side.

The top of the nozzle 9, in which is the outlet 10,

may be a separate cap as shown, or it may be integral with the body. Obliquely across the throat of the nozzle I fix a deflecting plate 11. This deflector presents a projected area to the flow of steam considerably less than the sectional 60 area of the throat of the nozzle; so that steam can pass freely around the plate to the outlet 10 and to the stack, while a part of it is deflected into the side opening 8 of the nozzle.

65 Mounted on the nozzle 6, and at the flanged side openings 7 and 8, is the bent tube 16. The upper part 17 of this tube is in the form of an arc of a circle; the lower parts 18 form tangents to said circle; and to the ends of the tangential portions I weld the short arms 20 and 21. 70 The ends of the arms are flanged as at 22, and on the arms are the loose flanges 23. When the loose flanges 23 are bolted up to the flanged outlets 7 and 8 of the nozzle 6, the tube flanges 22 form gaskets between them. If the flange 75 bolts are loosened, the flanged arms 20 and 21 may be rotated while the flanges 23 are still held in place. This joint is what is known as a Vanstone joint. Arranged concentrically about the steam tube 16 is the water tube or water 80 jacket 31. These two tubes are spaced and held apart at the top by the spacers 32, which may be made of short sections of pipe, as shown; and which may be conveniently welded to the smaller tube 16. At its extremities the water 85 jacket 31 has tangential portions 19; and it is here spaced from the steam tube 16 by the annular rings 33, which are welded to both tube 16 and jacket 31 to completely close the annular 90 space between them.

95 The bent tubes 16 and 31, forming the heater body, are shown in Figure II in an erect position so that their form and arrangement may be easily understood. When the heater is installed in a locomotive smoke box these tubes stand in an inclined position, as in Figure I, so that the exhaust steam leaving the nozzle 9 shall have an unobstructed path to the stack; and so that the heater may be installed with ease, and be adapted to locomotives of more than one size. I secure the heater in the inclined position by means of the strap 36, which I clamp around the tube 31, and the free end of which I bolt to the smoke-box shell by the bolt 25. In case of needed repairs to tubes, superheater, or other equipment at the front end of the boiler, after loosening the flanges 23, disconnecting water lines, and taking out the strap bolt 25, the heater body can be swung down and out of the way; 100 105 110

and as easily returned to its place when the repairs are completed.

Water connections 34 and 35 are made at the lower ends of the water tube. These are located on both sides of the heater, so that the connections may be made on whichever side is most convenient. I have shown the connections 34 on the tube-plate side of the heater, and the connections 35 on the other side or front of the heater. The unused connections may be capped; or they may be used for drainage and wash-out connections.

On the lower side of the arms 20 and 21 are drainage connections 41; and between these connections and the nozzle 6 are dams 42, the object of which is to prevent any occasional flood of condensate from passing the dams 42 and entering the engine cylinder by way of the cylinder outlet 5.

20 The spark-arrester 43 is shown in its usual location. The diaphragm plate 44 is cut to fit around the heater. In Figure II 45, 45, indicate the boiler tubes.

In the drawings I have shown the deflector 11 as a plate. The object of this plate is to deflect steam to the steam tube 16. The deflector causes a differential in pressure between the two openings 7 and 8; and this differential causes a flow of steam through the tube. If there were no deflector steam would enter the tube; but the results would not be the same as less heat would be transmitted through the tube to the water surrounding it, and as the tube would be apt to become more or less air-bound. The establishing of this differential pressure is therefore of value. It has already been noted that the back-pressure on the engine must not be sensibly increased. Though I show a deflector in the form of a plate 11, I can make it of other materials and forms; for instance, a piece of heavy wire screen set obliquely across the nozzle throat. The wire screen will allow steam to pass to the stack, and will at the same time set up the differential between the inlet opening 8 and the outlet opening 7. There will also be a difference in pressure at these two points due to the condensation of steam in the tube.

In operation: Feed-water enters and leaves the water tube 31 by the connections 34 and 35. The heater being located directly in the path of the products of combustion, heat is transmitted through walls of tube 31 to the water in the annular space between tube 31 and steam tube 16. At the same time steam flows from the cylinder outlet 5, passes upward through nozzle 6; part is deflected by deflector 11 into the arm 21 of tube 16, and part passes the deflector 11 and goes to the nozzle opening 10, and to the stack. The steam which enters tube 16 at opening 8 flows around the tube to outlet 7; a part of it is condensed and the remainder goes out at nozzle opening 10. The path of the steam is indicated by arrows.

In the drawings I have shown the steam tube 16 and the water tube 31 as if bent to form. It would be a very expensive operation to bend or forge tubes of such diameter to such radii; and in any event it will be necessary to add the tangential portions after the tube has been inserted within the outer tube; a possible, but again an expensive operation. There have recently been placed upon the marked forged pipe bends with ends prepared for welding. I use these pipe bends, welding them together to form the two curved tubes. The tangential portions 18 and 19 are weld-

ed to the curved portions of the tubes. The flanges 22 are formed on, or are welded to, the arms 20 and 21; the loose flanges 23 are slipped on to the arms; the drain connections 41 are then welded to the arms 20 and 21; and the arms are then welded to the tangential portions 18. The deflector plate 11 is carried by an arm or rod 38, which may be riveted or bolted to the nozzle casting at both ends. In my drawings I have shown the upper end of the rod 38 bent, and dropped into a slot cut in the upper rim of the nozzle casting 6.

My heater has been installed in a locomotive; and comparative tests have been made, with and without my heater. The results of a large number of such tests have shown an average increased boiler and superheater efficiency of more than ten and one half per cent. These tests have proved that my heater is simple in construction; that it is easy to install; that it utilizes the waste heat in the flue gases without interfering with draft; and that it also utilizes waste heat from the exhaust steam without perceptibly increasing the exhaust pressure in the cylinder.

In the drawings and specifications I have described the form of my heater as partly that of an arc of a circle, with tangents and arms. The heater may be of any convenient form; for instance, annular, elliptical, rectangular. My object is to use a shape which it may be easy to construct and which shall suitably conform to the space which it is to occupy. The form of the inner or smaller pipe is broadly speaking that of a loop, and I have so referred to it in the claims. I have also referred to the body or main casting 110 of the nozzle 6 as the exhaust pipe; since it is so referred to by railroad men when the nozzle proper, 9, is made a separate part.

I claim:

1. A feed water heater comprising an exhaust pipe having a passage for steam therethrough; opposed branch pipes connected to the exhaust pipe intermediate its length; a deflector so arranged in the exhaust pipe as to deflect a part of the steam entering the exhaust pipe into one of the branches, and also so arranged as to deflect steam entering the exhaust pipe by the other branch toward the nozzle of the exhaust pipe; a looped steam pipe connected at its ends to the branch pipes; a water jacket mounted concentrically upon the looped steam pipe; and connections for connecting the water jacket into a water line.

2. A feed water heater comprising an exhaust pipe having a passage for steam therethrough; opposed branch pipes connected to the exhaust pipe intermediate its length; a deflector so arranged in the exhaust pipe as to deflect a part of the steam entering the exhaust pipe into one of the branches; a looped steam pipe connected at its ends to the opposed branch pipes by swing joints; a water jacket mounted concentrically upon the looped steam pipe; connections for connecting the water jacket into a water line; and means for securing the looped and jacketed steam pipe in position.

3. A feed water heater comprising an exhaust pipe having a passage for steam therethrough; opposed and horizontally disposed branch pipes connected to the exhaust pipe intermediate its length; a deflector so arranged in the exhaust pipe as to deflect a part of the steam entering the exhaust pipe into one of the branches; a looped steam pipe connected at its ends to the opposed branch pipes by adjustable joints; a water jacket 150

- mounted concentrically upon the looped steam pipe; and connections for connecting the water jacket into a water line.
4. A feed water heater comprising an exhaust pipe having a vertical passage for steam therethrough; opposed and horizontally disposed branch pipes connected to the exhaust pipe intermediate its length; a fixed deflector so arranged in the exhaust pipe as to deflect a part of the steam entering the exhaust pipe into one of the branches; a looped steam pipe connected at its ends to the opposed branch pipes; a water jacket mounted concentrically upon the looped steam pipe; and connections for connecting the water jacket into a water line.
5. A feed water heater comprising an exhaust pipe having a vertical passage for steam therethrough; opposed and horizontally disposed branch pipes connected to the exhaust pipe intermediate its length; a fixed deflector so arranged in the exhaust pipe as to deflect a part of the steam entering the exhaust pipe into one of the branches; a looped steam pipe connected at its ends to the opposed branch pipes; by means of adjustable joints; a water jacket mounted concentrically upon the looped steam pipe; and water connections on the water jacket.
6. A feed water heater comprising an exhaust pipe having a vertical passage for steam therethrough; opposed and horizontally disposed branch pipes connected to the exhaust pipe intermediate its length; a fixed deflector so arranged in the exhaust pipe as to deflect a part of the steam entering the exhaust pipe into one of the branches and also so arranged as to deflect steam entering the exhaust pipe by the other branch toward the nozzle of the exhaust pipe; a looped steam pipe connected at its ends by swing joints to the branch pipes; a water jacket mounted concentrically on the looped steam pipe; water connections on the water jacket; and means arranged to hold the looped steam pipe and the exhaust pipe in relative operating position.
7. A feed water heater comprising an exhaust pipe having a passage for steam therethrough; opposed branch pipes connected to the exhaust pipe intermediate its length; a looped steam pipe connected at its ends to the branch pipes by means of adjustable swing-joints; a water jacket mounted concentrically on the looped steam pipe; and water connections on the jacket.
8. A locomotive feed water heater comprising an exhaust pipe mounted on the cylinder exhaust ports and in line with the stack; opposed branch pipes connected with the exhaust pipe intermediate its length; a looped steam pipe set up on and connected at its ends with the said branch pipes but inclined at an angle to clear the way between the exhaust pipe and the stack; and a water jacket mounted concentrically on the looped pipe and provided with water connections.
9. A locomotive feed water heater comprising an exhaust pipe mounted on the cylinder exhaust ports and in line with the stack; opposed branch pipes connected with the exhaust pipe intermediate its length; a looped steam pipe set up on and connected at its ends with the said branch pipes but inclined at an angle to clear the way between the exhaust pipe and the stack; a deflector so arranged in the exhaust pipe as to deflect a part of the steam entering the base of the exhaust pipe into one of the branch pipes; and a water jacket mounted concentrically upon the looped steam pipe and provided with water connections.
10. A locomotive feed water heater comprising an exhaust pipe mounted on the cylinder exhaust ports and in line with the stack; opposed branch pipes connected with the exhaust pipe intermediate its length; a looped steam pipe set up on and connected at its ends with the said branch pipes but inclined at an angle from the vertical to clear the way between the exhaust pipe and the stack; a deflector in the exhaust pipe proportioned and positioned so as to deflect a part of the exhaust steam entering at the base of the exhaust pipe into one of the branch pipes and also so proportioned and positioned as to deflect steam entering the exhaust pipe by the other branch toward the nozzle of the exhaust pipe; and a water jacket mounted concentrically upon the looped steam pipe and provided with water connections.
11. In a locomotive feed water heater, an exhaust pipe with blast nozzle, horizontally and directly opposed branch pipes connected with the main exhaust pipe intermediate its length, an undivided looped steam pipe connected at its ends to the branch pipes by means of adjustable swing-joints, and a water jacket mounted on the steam pipe.
